WINDSHIELD DEFROSTER

Linus E. Russell, Springfield, Ohio

Application December 18, 1948, Serial No. 150,239

Term of patent 14 years

(Cl. D14—6)

To all whom it may concern:

Be it known that I, Linus E. Russell, a citizen of the United States, residing at Springfield, Clark County, Ohio, have invented a new, original, and ornamental Design for a Windshield Defroster, of which the following is a specification, reference being had to the accompanying drawing, forming a part thereof, in which Fig. 1 is a perspective view of a windshield defroster embodying my new design;

Fig. 2 is a side view thereof;

Fig. 3 is a front view thereof; and

Fig. 4 is a bottom view thereof.

The dotted line disclosure in Fig. 1 is for illustrative purposes only.

I claim:

The ornamental design for a windshield defroster, substantially as shown and described.
LINUS E. RUSSELL.
